BATHING EQUIPMENT

Filed July 31, 1928

UNITED STATES PATENT OFFICE

EDWARD TAYLOR, OF BROOKLYN, NEW YORK

BATHING EQUIPMENT

Application filed July 31, 1928. Serial No. 296,488.

This invention relates to bathing equipment for infants, and the object of the invention is to provide an apparatus for facilitating bathing and dressing infants, which, 5 when not in use, forms a traveling case of sufficient capacity for carrying all the clothes and other equipment necessary when traveling with an infant.

More particularly the objects of the invention are to provide an apparatus of this class which may be used in conjunction with ordinary bath tubs to provide a ready means for giving an infant a shower or spray bath; to provide a dressing tray alongside, to which 15 the infant may be readily transferred for dressing; and further to provide an article of this class which occupies but little space, which may be readily cleaned, which is light and strong, which may be easily handled, 20 and which when closed up forms a traveling case of about the capacity of a good sized suit case.

A further object of the invention is to provide a special form of spray nozzle for use 25 in connection with the bath tub faucet, the spray being designed to lie flat and also to produce a converging rather than a diverging spray, for reasons which will be later explained.

30 In the accompanying drawings I have illustrated a preferred embodiment of my invention, and in said drawings

Fig. 1 is a perspective view showing the apparatus ready for use;

35 Fig. 2 is a sectional view on the line 2—2 of Fig. 1, showing the action of the spray;

Fig. 3 is an enlarged detail view of the spray nozzle;

40 Fig. 4 is a perspective view of the apparatus ready for packing;

Fig. 5 is a sectional view showing the apparatus when folded to form a traveling case; and

45 Fig. 6 is a perspective view showing the apparatus enclosed in its detachable cover.

Referring to the drawings, particularly to Fig. 1, my invention consists essentially of two rectangular frames 1 and 2, which are of a length to fit across the top of a standard 50 bath tub. Fully ninety-five percent of the

bath tubs sold today are within the range of thirty to thirty-two inches in width, the standard size being thirty inches. The frames 1 and 2 will therefore preferably be made thirty-three inches in length over all, 55 which allows the ends to rest on the rim of a thirty-two inch tub without projecting too far over the edge of a thirty-inch tub. The frames may be any convenient width, for example, twenty-four inches, and are hinged together as indicated at 3.

On the side opposite from the hinge the frame 1 is provided with a covering of stout copper cloth of fairly close mesh, as indicated at 4. The frames are preferably made 60 of wooden bars about one and a quarter inches by two inches, and the screening is preferably fastened in the edge of one side of the frame 1 by forcing the edge of the screen onto a kerf in the face of the frame and then driving screws or nails 5 from the inside so as to leave a clear margin of wood around the outside of the frame.

The frame 2 is similarly covered with a 65 sheet 6 of heavy duck, so that when the frames are open as far as permitted by the hinge 3, they form a continuous table across the bath tub, half of which is covered with wire screening and the other half of which is covered with duck.

In order to hold the frames in place on the tube I preferably provide a set of U-shaped holders 7. These holders are formed of spring members curved as shown, and with the ends turned laterally as indicated at 8 in Fig. 5, to fit into holes which are bored 70 in the inner face of the longitudinal members of the frames, as indicated at 9 in Fig. 2. A series of holes is provided so that the supports may be differently placed to accommodate tubs of different widths. The holes are spaced apart somewhat less than the normal distance between the free ends of the holders, so that the holders will be under tension 75 when in the holes and remain firmly in place. Ordinarily one pair of holders is placed in the outer or top frame member of one frame and the other pair in the inner or bottom member of the other frame, so that when the frames are close together as shown in

Fig. 5, the holders will not interfere with each other. Holes are however provided in all the longitudinal frame members so that the holders 7 may be placed wherever necessary to best hold the frames in place.

5 The outfit preferably includes a spray nozzle of the special form illustrated in Fig. 3. As shown, the spray nozzle consists of a ring 10 of pipe or tubing with holes for the discharge of water on the inside of the ring below the middle diameter of the tube so that the streams of water will form a converging spray as shown in Fig. 2.

By this arrangement all danger of splashing the water onto the dressing tray is avoided. What is more important, the spray lies flat on the screen when not held in the hand and all the water is discharged through the screen.

20 The end of the tubing 10 which conducts the water to the perforated ring is preferably long enough to provide a handle between the ring and the end to which the hose is attached whereby the spray may be used after 25 the fashion of a fountain brush in directing the water wherever desired.

In using the apparatus a thin cloth may be spread over the screen, but the infant may be laid directly on the screen without discomfort. After bathing, the infant may be readily transferred to the dry dressing tray alongside, where it may be conveniently dressed.

35 The outfit is particularly convenient for traveling, the two frames, when folded together, forming a traveling case which is sufficiently commodious to carry all the necessary paraphernalia for the infant. In an ordinary sized apparatus the interior of the case is slightly over eighteen inches long, 40 thirty inches high, and four inches deep. To facilitate carrying the outfit the frames are preferably provided with handles 11 rigidly attached to the outside longitudinal frame members and shaped so that when the frame members are folded together as shown in Fig. 45 5, the two handle sections form a tubular circular handle.

For convenience in packing, I may provide a number of metal division strips 12 which, as 50 shown in Fig. 4, may be inserted at their ends in kerfs in the side frame members and thus divide the frame into a number of compartments. If the articles to be packed in the 55 frame do not permit use of the division strips, the strips may be readily removed from the kerfs and laid flat against the canvas, the ends of the strips slipping between the canvas and the frame, whereby the strips are held in place but are entirely out of the way.

I preferably provide a cover for the folded frames as shown at 13 in Fig. 6. This cover may be made of any suitable material such as cloth or fabrikoid. The cover shown is for 65 convenience provided with so-called hookless

or "Zipper" fasteners extending from a point about the middle of the end frames to the adjacent end of the handles, and a strap with snap buttons as shown at 14 is provided to hook the two sides of the cover together between the handles. When enclosed in its cover the outfit presents a neat and attractive appearance not distinguishable from a covered traveling bag.

In the appended claims I have referred to 75 the covering for the frame 1 as wire cloth. It will be understood of course that the term is used generically and that any suitable fabric of sufficient strength and permitting the free passage of water therethrough may be 80 employed instead.

I claim:

1. A combined carrying case and bath table comprising two frames, one of said frames having a covering on its outer side of material having openings throughout substantially its entire area for the free passage of water, the other of said frames having a covering of fabric on its outer side, said frames being hinged to each other at one marginal edge so that said frames may be swung to substantially coplanar position for use as a bathing apparatus.

2. A combined carrying case and bath table comprising two frames, one of said frames having a covering on its outer side of material having openings throughout substantially its entire area for the free passage of water, the other of said frames having a covering of fabric on its outer side, said frames being hinged to each other at one marginal edge so that said frames may be swung to substantially coplanar position for use as a bathing apparatus, and means carried by said frames for preventing lateral displacement of said frames when said frames are swung to substantially coplanar position and placed on a bath tub.

3. A combined carrying case and bath table comprising two frames, one of said frames having a covering on its outer side of material having openings throughout substantially its entire area for the free passage of water, the other of said frames having a covering of fabric on its outer side, said frames being hinged to each other at one marginal edge so that said frames may be swung to substantially coplanar position for use as a bathing apparatus, and detachable and adjustable members carried by said frames for preventing lateral displacement of said frames when said frames are swung to substantially coplanar position and placed on a bath tub.

4. A combined carrying case and bath table comprising two frames, one of said frames having a covering on its outer side of woven wire fabric of a mesh to permit the free passage of water therethrough, the other of said frames having a covering of fabric

on its outer side, said frames being hinged to each other at one marginal edge so that said frames may be swung to substantially coplanar position for use as a bathing apparatus.

5. A bathing table comprising a pair of hinged frames, one of said frames having a covering on one side thereof of material having openings throughout substantially its entire area for the free passage of water, the other of said frames having a covering of fabric on one side thereof.

6. In an article of the class described, a pair of rectangular frames, hinges connecting said frames whereby they may be closed together in superimposed position or opened to lie in the same plane, fabric coverings attached to the said frames on the faces forming the outer sides thereof when the frames are in closed position, one of said fabrics being composed of material having small openings throughout substantially its area, said frames being of such depth that the two covered frames constitute a packing case having unobstructed compartments of substantial capacity.

7. In an article of the class described, a pair of rectangular frames, hinges connecting said frames whereby they may be closed together in superimposed position or opened to lie in the same plane, fabric coverings attached to the said frames on the faces forming the outer sides thereof when the frames are in closed position, one of said fabrics consisting of an open-mesh woven wire, said frames being of such depth that the two covered frames constitute a packing case having unobstructed compartments of substantial capacity.

40. 8. An article of the class described, comprising two rectangular frames hinged together along one longitudinal edge of each to fold together or open out into the same plane, said frames being covered with fabric, the fabric of one of said frames permitting the free passage of water therethrough, handles on the longitudinal members of said frames opposite from the said hinges, and removable division strips supported in said frames for dividing them into a plurality of compartments.

In testimony whereof I affix my signature.
EDWARD TAYLOR.
